HENRY S. BACK, OF RETSIL, WASHINGTON.

PORTABLE GOLD-SAVING MACHINE.

Application filed February 23, 1922. Serial No. 538,510.

To all whom it may concern:

Be it known that I, HENRY S. BACK, a citizen of the United States, residing at Retsil, in the county of Kitsap and State of Washington, have invented a new and useful Portable Gold-Saving Machine, of which the following is a specification.

My invention has reference to improvements in gold saving machines of the rocker variety; and has for its objects, the provision of a rocker having a chamber wherein angular riffles of copper are arranged in a special way on the four copper walls of the chamber, and block riffles of the same material disposed therebetween, which, by reason of their construction and the use of amalgam on their exposed surfaces, will save not only the coarser gold from auriferous earth, sand or other material, but the fine or flour gold which, heretofore, in the ordinary type of rocker has been lost through the tailings. Further to provide, a machine that is easily transportable, and requiring no special skill to use it.

25 In the accompanying drawings—

Figure 1 is a plan view of the machine, the top portion of said chamber and some of its supports being partly broken away to show the arrangement of the angular riffles

30 and the block riffles seated thereon.

Fig. 2, a longitudinal section, drawn on the line 2—2, of Fig. 1, the riddle being slightly raised above the rocker box.

Fig. 3, a view of the machine in perspective.

Fig. 4, a plan view of the top and bottom of the chamber, particularly showing the angular riffles, the location of the block riffles being indicated by dotted lines.

40 Fig. 5, a cross-section drawn on the line 5—5, of Fig. 1, being a view of that portion of the machine between the riddle and the chamber, looking toward the receiving end of the chamber, and indicating the means for 45 securing and holding the four walls of the chamber in place, including one of the rockers and the handles.

Fig. 6, a plan view of one of the block riffles, consisting of four separable parts assembled as a unit, the front formed, as indicated by dotted lines to simulate a right and left plow mold board, and the back concave

in form; also showing a gold saving recess extending around its upper edge.

Fig. 7, an elevation of the same, further illustrating the front of the block as assembled, and also showing a gold saving recess extending around the upper edge of each of its four parts.

Fig. 8, a perspective of one of the sides of 60 the chamber.

Fig. 9, a side elevation of the device complete, as mounted on supports to afford bearings for the rockers, and to give the proper inclination to the rocker box.

Referring more particularly to the drawings, 1 denotes the rocker box, and 2 a riddle having preferably a one inch mesh. It is hinged to the box, as indicated at 3, to enable the riddle to be lifted and to discharge 70 therefrom large rocks, leaves, moss and such extraneous matter not adapted to go through the machine. It is supported in a horizontal position in the box further by the blocks 4. The rockers 5 are located adjacent each end 75 of the box, as shown, the discharge opening for the tailings at one end of the box is denoted by 6, and the handles by 7. These handles are bolted to the box and held by the winged nuts 8, so that they can be readily 80 demounted, if desired.

The essential feature of the invention consists of a gold saving chamber 10 detachably mounted in the box, its receiving end adjacent the riddle. It comprises four plates of 85 copper, the bottom plate seated in the bed of the box, the two side plates seated on the bottom plate and also supported by the sides of the box, and the top plate seated on the side plates and further supported by a series 90 of block riffles placed between the top and bottom plates. Means are also provided for detachably securing said chamber in the box, as hereinafter described.

The bottom plate 11 is provided with a 95 plurality of riffles, which I term angular riffles. They are of copper, preferably square in cross section, and, in the present embodiment of the invention, are arranged as shown in Fig. 4. The first series, designated as 12, begin flush with the front of the plate and extend at an angle of between 100 30 and 35 degrees in equally spaced relation to within a short distance of the left

side edge of the plate, the adjacent terminals of the riffles being spaced from said side edge a distance about equal to the space between each riffle. This construction permits gold or material in the rocker to work its way down around said terminals and discharge into the second series of riffles designated as 13. As it will be noted, the forward terminals of the second series are spaced away from the first series. They are located on the plate in spaced angular relation similar to the first series, but in reversed position, the rearward terminals, except two, being spaced from the right side edge, as the first series are spaced from the left side edge, and a portion of them extending flush with the back edge. Said two riffles extend to the side edge, to afford, in connection with one riffle of the first series, supports for the side plate to be mounted thereon. The third series, designated as 14, in the same angular spaced relation as the second series, extend from the left side edge to the back edge of the plate. 15 denotes a riffle placed particularly as one of the supports for the side plate to be carried on said side. The top plate of the chamber is of identically the same construction as the bottom plate, just described.

30 The left side plate of the chamber, looking from its receiving end, is shown in Fig. 8, its designating numeral 16 being located at its front end. It is provided with a plurality of angular riffles 17 extending upwardly, and at angles less acute than those on the top and bottom plates. The right side plate also carries riffles in the same relative positions within the chamber. Placer gold, when agitated by water, has a tendency to work its way upward, especially the fine or flour gold, which this machine is designed to save. Having in view this characteristic, said riffles are so directed as to afford resting places for the gold that may 40 work its way up the sides.

45 What I term a block riffle is shown in detail in Figs. 6 and 7, and designated as 20. It consists of four parts, each having on its upper periphery a cut away portion 21, Fig. 6, around its edge, of a depth, preferably, not exceeding the thickness of an ordinary piece of paper, which, in connection with the part placed immediately above, forms a recess or crevice, as indicated in 50 Fig. 7, especially adapted to catch and retain the fine gold. The cut away portion on the top block, will form a crevice in connection with the top of the chamber, when a block riffle is mounted therein, as described 55 shortly. Said parts are so formed that when assembled together as a unit, as indicated in Figs. 6 and 7, the face of the block 22 simulates the contour of a double mold board plow, and the back of the block 23 60 is concave in form. Under this construc-

tion, when water and material is forced against the face of the block, the same is turned over by the plow like face, and striking against the concave back of a block in front, as assembled in the chamber, an eddy 70 is formed, which serves to further agitate the water and material.

In assembling the chamber, the four plates and the parts which make up the block riffles are first amalgamated. The 75 bottom plate is then placed in the bed of the rocker box adjacent the riddle, as shown in Fig. 1. The block riffles, being made of copper, possess sufficient weight so that the four separable parts will stack together, 80 and can be readily handled. In the present embodiment of the invention, three of the block riffles, assembled as shown in Fig. 7, are placed in a row on the bottom plate, spaced slightly away from the receiving end 85 of the chamber, and an equal distance apart from each other and the sides of the plate, their faces directed toward said end. Two more of the block riffles are then placed back of the first row, in staggered relation 90 therewith, and spaced therefrom approximately the same distance as the first row is spaced from the front edge of the plate. To effect this staggered relation, but two complete block riffles can be placed in the 95 second row, and in order to take care of the open spaces left on either side and to properly divert the water and material toward the center of the chamber, a half block riffle 24, Fig. 1, is placed on either side of the 100 plate and adjacent the edge. The second row thus comprises two units of block riffles, and two half block riffles, made by cutting one unit in half vertically, the latter being so placed that the respective right and left 105 plow portions face the receiving end of the chamber and curve inwardly. The dotted line at 24, Fig. 1 indicates the form of a half block as thus made and assembled, the corresponding block at the other end of the 110 row being reversely curved. The two remaining rows of block riffles are placed identically the same as the first two rows, comprising in all 10 block riffles complete, and four half block riffles. 115

The two side plates are then placed on either side of the bottom plate so as to enclose the block riffles and receive support from the sides of the rocker box and certain ends of the angular riffles. To give stability 120 to the top plate and to afford a cover for the chamber, a board 30, conforming to the outlines of said plate, is secured thereto. The same is then mounted on the top of the block riffles and the sides, thus making a 125 chamber rectangular in form, closely fitting the sides of the rocker box, having angular riffles on the top, bottom and sides, with block riffles interposed therebetween, and in staggered relation. To secure this chamber 130

in place, a pair of cleats 31 are provided and placed adjacent each end of the top. Blocks 32, of a height sufficient to form a plane surface with the side edges of the rocker box, 5 are placed at each end of said cleats, and the whole clamped together and held in place through the cross pieces 33 extending transversely over the top and under the bed of the rocker box, secured by the bolts 34, and 10 the winged nuts 35.

In order that the tailings may not discharge too freely and to insure a proper treatment of the material, an adjustable tail-board is provided, and located adjacent the 15 discharge end of the chamber. It comprises a cleat 40, extending across said end, and of a height obviously less than the height of the chamber. It is held in place by a vertically extending cleat 41 on each side of the 20 rocker box, and a wedge 42, Fig. 3, placed between the end of the cleat 40 and a side of the box. This permits the tailboard to be readily raised, lowered or removed, as desired.

25 In Fig. 9, the machine is shown as mounted on the supports 50 and 51, ready for use. For best results, it should be so placed as to work on an incline of one foot in six, thus giving a proper head to the water and 30 material, and an effective discharge for the tailings.

In utilizing the invention, assembled as 35 described, auriferous material is shoveled into the riddle, and with the proper application of water, the mesh will eliminate matter not adapted for treatment by the machine, such as large stones, moss, leaves, etc. The material to be worked then enters the chamber, which, it will be remembered, is 40 amalgamated throughout. Such material, when mingled with water, carries the gold through its body at different levels, according to its character. For instance, the heavier gold will naturally seek the bottom 45 or lower level, and possibly will be caught by the first amalgam it comes in contact with. Floating in the center is the lighter gold, and floating on top is the very fine, or flour gold, which this machine is particularly 50 adapted to save, and which ordinarily, in gold saving machines, has passed out through the tailings. Vast quantities of the black, gold bearing sands exist on the ocean beaches, but it has not been profitable to 55 work this material on account of the seeming impossibility of saving such gold.

Located as it is on the beaches, and necessarily coming in contact with animal substances, it is what placer miners term 60 "greasy gold," which, by reason of its oily nature, has no affinity for amalgam. One purpose of this machine is, to treat such gold by agitation in water so as to relieve it of some of its oily enveloping substances 65 and clean it sufficiently to enable it to be

taken up by the quicksilver or other amalgam used. Further, to provide lodgment places for it, so that it can be readily saved. To this end, I provide the gold saving chamber.

70 When the material, which word in this connection also includes water, enters the chamber and is agitated by the rocking of the machine, it comes in contact with the plough shaped faces of the block riffles, the 75 forms of which are designed to turn said material over. As the same goes down to the next row of block riffles it gains headway, is again turned over, and coming in contact with the concave backs of the preceding row of block riffles eddies are formed which serve to further agitate said material, the same continuing throughout the length of the chamber. The angular riffles form under currents, and the action of the water 80 and material passing through and over them, also contribute to the treatment of the material, in agitating it, making the gold receptive to the action of amalgam, by washing it, and in affording lodgment places for 85 it. As noted, the first series of angular riffles communicates with the second series, so any gold not retained by the first series can work its way down around the terminals of said riffles into the second series, the 90 action of the water all the time taking from the gold its oily characteristics and putting it in condition to be taken up by the riffles below.

95 Gold, when subjected to the action of moving water, has a tendency to work upward, and the side plates, to take care of this properly, have riffles placed at slight angles directed upwardly, to afford adequate resting places for gold that may lodge thereon.

100 The block riffles perform a further and most useful function, in that they each provide crevices many inches in extent for catching and holding the fine or flour gold, which, in auriferous material, subject to 105 placer mining, is estimated to be fully 50 per cent of the gold contained therein. In fact, the saving of this class of gold, is the one feature which will make the working of many placer propositions profitable. Much 110 of this gold is invisible to the naked eye, and the crevices in the block riffles, approximating in width the thickness of a sheet of paper, and amalgamated, are particularly 115 adapted to retain this gold so necessary to 120 a profitable working of much placer ground.

To make a clean up, the chamber is demounted and each block riffle separated into its four parts, when the amalgam can be removed from said parts, and the four plates, 125 and the gold saved in a manner well known to those acquainted with the art.

130 It requires but a superficial knowledge of placer mining to use this device, so with gold bearing material to work with, I contemplate

that any one able to place the material in the riddle, apply the water and rock the box, can make good wages, or more, from digging which formerly could not be worked with profit.

Changes in and modifications of the construction described may be made without departing from the spirit of my invention, or sacrificing its advantages, hence I ask that 10 I be not confined to the specific structure set forth.

I claim:

- 15 1. In a device of the class described having a rocker box, a riddle, and a discharge opening for tailings, a gold saving chamber communicating with the riddle and said opening, having a bottom member carrying a series of riffles disposed in angular relation, adapted to discharge into another series 20 of riffles disposed in reversed angular relation, a top member of similar construction, a pair of side members having a plurality of riffles disposed in angular relation, extending upwardly and directed toward the 25 discharge end of the chamber, a plurality of vertically extending riffles interposed between said members, having gold saving crevices, and means for detachably mounting said chamber in the rocker box.
- 30 2. In a device of the class described, a gold saving chamber, comprising a bottom member having a series of riffles disposed in spaced angular relation, a second series of riffles disposed in reversed angular relation 35 to the first series and communicating therewith, a top member having riffles of like construction, a pair of side members having

riffles disposed in spaced angular relation, extending upwardly and directed toward the discharge end of the chamber, supports 40 therefor, a cover for the top, and means for detachably securing the chamber in a rocker box.

3. In a device of the class described, a block riffle, having a face terminating in a 45 medial vertically extending edge portion with reversely curved reentrant sides gradually merging in the vertical sides of the block, also curving upwardly and gradually merging on either side to a point adjacent the upper front corners of the block, and curving downwardly and gradually merging on either side to a point adjacent the lower front corners thereof, the back of said block concave in form, and a narrow gold saving 50 recess extending around an edge of each block.

4. In a device of the class described, a block riffle, having a plurality of superimposed parts, each provided on its upper 55 periphery, and around the edge thereof, with a recessed portion defining in connection with the part located immediately above, a gold saving crevice extending around each part.

5. In a gold saving machine having a rocker box and a riddle, a demountable gold saving chamber, provided with riffles on its top, bottom and sides, and interposed therebetween, a plurality of vertically extending 60 members having narrow gold saving recesses, and means for detachably securing said chamber in the rocker box.

HENRY S. BACK.
